UNITED STATES PATENT OFFICE

2,523,715

BRASSIÈRE

Isidore Panes, New York, N. Y.

Application March 24, 1948, Serial No. 16,779

2 Claims. (Cl. 2—42)

1

This invention relates to brassières, bandeaux and closely analagous garments having breast pockets.

The principal object of the present invention is the provision of a garment of the indicated character with means which yieldingly keeps the garment up in place on the body of the wearer in such manner that the breasts of the wearer are supported with the desired uplift and which are constrained to a spread apart or separated relation.

Another object of this invention is the provision of means of the indicated character in a brassière or like garment which is well suited for economic manufacture.

With the foregoing, other objects and advantages will appear when the following specification is read in conjunction with the accompanying drawing, in which:

Fig. 1 is a front view of a brassière embodying the features of the present invention.

Fig. 2 is an enlarged fragmentary front view of one of the pockets of the brassière and connected parts illustrating the manner in which the pocket is put under stress.

Fig. 3 is a sectional view taken on the line 3—3 of Fig. 2.

Fig. 4 is a sectional view taken on the line 4—4 of Fig. 2.

Shown in the drawing is a brassière comprising a body band 10 with cups or curviform pockets 11 for the busts or breasts. One end of the band 10 has secured thereto a short strip 14 of elastic material doubled upon itself and a tab 15 having a series of eyelets 16 has one end secured to the outer end of the loop formed by the strip 14. The hook 13 is engageable in any one of the eyelets 16 to secure the brassière properly adjusted according to size around the torso of the wearer.

In accordance with the present invention there are provided shoulder straps 17 comprising main inelastic portions 18 connected with elastic portions 19 of strip material, by buckles 20. These buckles enable adjustments in the length of the straps 17. The portions 19 are doubled upon themselves forming inverted V loops to receive the buckles 20, and the ends of the strip material constituting the portions or loops 19 are secured to the band 10 by stitching at the top of the pockets 11, as at 21.

Guides or tunnels 22 extend partly around the pockets 11 from a point at the top of the pockets, curving downwardly and laterally rearward to an intermediate point of the band 10. The guides or tunnels 22 are formed by lines of stitching 23

2

which extend through the material of the band 10 and the opposite side edge portions of strips 24 of fabric arranged on the inside of the band. The tunnels 22 at the top of the pockets 11 terminate in openings 25 in the material of the pockets.

Inelastic draw strings, cords or strips 26 of textile material are loosely arranged for sliding movement in the tunnels 22. Strips are used in the present instance which have their opposite ends secured by stitching to the band 10 and the elastic portions 19 of the shoulder straps 17, as at 27 and 28. The upper ends of the strips 26 extend through the openings 25 and are joined to the portions 19 at intermediate points of the latter.

A brassière having the features set forth above may be placed around the wearer's body with the straps 17 arranged over the shoulders. The hook 20 13 is engaged in the selected eyelet 16 which puts the band 10 under tension. The straps 17 exert an upward pull on the band 10 at the front and back, but the band 10 is kept from moving upwardly, or in other words, stays put because of the upward flare of the torso and the tension exerted by the elastic material 12 and 14. The straps 17 being under tension cause the elastic portions 19 to stretch, and as a consequence a pull is exerted on the upper ends of the strips 26. This causes both an upward and laterally outward strain on the pockets 11 and as a result the busts or breasts are held uplifted in a spread apart relation as intended.

The portions 19 of the shoulder straps 17 being made of elastic strips doubled upon themselves afford strong elastic connections of the straps 17 with the band 10. The upper ends of the draw strips 26 are secured at 28 to the portions 19 near the point of connection of the portions 18 with the portions 19. The material of the portions 19 below the points of attachment 28 as affected by the adjusted length of the shoulder straps 17 determines the amount of stretch of the portions 19 and the uptake of the strips 26. The shoulder straps 17 together with the strips 26 not only hold the brassière up in place, but also function to keep the breasts of the wearer uplifted and separated with the desired effect.

I claim:

50 1. A garment including a body band having breast pockets, shoulder straps having their opposite ends connected with the band at the back and at the top of the pockets, each of said shoulder straps having an elastic portion, tunnels 55 formed on the band and extending downwardly

from the tops of the pockets around the pockets near the center of the band and then laterally to points on the band near its lower edge at the sides of the pockets, and inelastic draw strips extending loosely in the tunnels with their upper end portions passing out of the upper ends of the tunnels, said strips having their upper ends attached to the shoulder straps and their lower ends attached to the band at the lower ends of the tunnels, the provision and arrangement of parts being such that the shoulder straps keep the band up in place on the body of the wearer while the draw strips keep the breasts spaced apart when the garment is in use.

2. A garment as set forth in claim 1, wherein the elastic portions of the shoulder straps are

interposed between the band and inelastic portions of the straps, and the upper ends of the draw strips are attached to said elastic portions.

ISIDORE PANES.
